EX

DESIGN FOR A STAGE-SCENE.

Design No. 12,214, dated April 5, 1881.

UNITED STATES PATENT OFFICE.

THOMAS DALY, OF BOSTON, MASSACHUSETTS, ASSIGNOR OF ONE-HALF TO
JOHN P. SMITH, OF BROOKLYN, AND WILLIAM A. MESTAYER, OF NEW
YORK, N. Y.

DESIGN FOR A STAGE-SCENE.

SPECIFICATION forming part of Design No. 12,214, dated April 5, 1881.

Application filed March 10, 1881. Term of patent 3½ years.

To all whom it may concern:

Be it known that I, THOMAS DALY, of Boston, Massachusetts, have originated a Design for a Stage-Scene, of which the following is a full, clear, and exact description, reference being had to the accompanying photographic illustration, making part of this specification.

My design consists in a theatrical scene across which extends a representation of an open side of a compartment railway-car, the running-gear beneath, and the supporting track-rails, as seen at *a a a* in the accompanying illustrations. As a perspective to the representation of the car in the foreground, an

appropriate landscape, trees *b b*, telegraph wires and poles *c c* are shown.

What I claim as new, and desire to secure by Letters Patent, is—

The design for a stage-scene, consisting, essentially, of a representation of an open side view of a compartment-car, its running-gear, and track *a a a*, with an appropriate background, substantially as shown in the accompanying illustration.

THOS. DALY.
